UNITED STATES PATENT OFFICE.

LEIGH S. BACHE, OF BOUNDBROOK, NEW JERSEY; MABEL S. BACHE, EXECUTRIX OF SAID LEIGH S. BACHE, DECEASED, ASSIGNOR TO BOUND BROOK OIL-LESS BEARING COMPANY, OF BOUNDBROOK, NEW JERSEY, A CORPORATION OF NEW JERSEY.

LUBRICATED COCK AND VALVE

1,261,469.

Specification of Letters Patent. Patented Apr. 2, 1918.

Application filed May 2, 1916. Serial No. 94,934.

To all whom it may concern:

Be it known that I, LEIGH S. BACHE, a citizen of the United States, residing at Boundbrook, in the county of Somerset and State of New Jersey, have invented new and useful Improvements in Lubricated Cocks and Valves, of which the following is a specification.

My present invention relates to improvements in cocks or valves, and more especially to those of the type employing a tapered plug rotatable in a casing, cocks or valves of such type being commonly employed in gas fixtures and connections.

Heretofore, much difficulty has been experienced with cocks or valves of this type owing to the tendency of the plug to stick in the casing and thus render rotation of the plug by hand very difficult. Efforts have been made to overcome this difficulty by applying a viscous substance, such as tallow, to the working face of the plug, but such efforts have proven unsatisfactory for the reasons that the tallow or other viscous substance has the property of becoming hard when old or cold and that no provision was made for a proper distribution of the tallow or viscous substance upon the relatively movable or rotatable working faces.

The primary object of the present invention is to provide a cock or valve of this type with lubricating means whereby proper distribution of the lubricant on the working faces is effectively maintained and the lubricant employed is solid, or substantially so, and is of a character capable of maintaining efficient lubricating properties, irrespective of its temperature or age, the lubricant, according to the present invention, being contained or retained in suitable pockets in one of the working faces of the cock in such manner that it constitutes in effect a part or continuation of such working face and its proper distribution between the working faces is thereby insured and maintained.

To these and other ends, the invention consists in certain improvements, and combinations and arrangements of parts, all as will be hereinafter more fully described, the novel features being pointed out particu-

larly in the claims at the end of the specification.

In the accompanying drawing:

Figure 1 represents a section through a 55 cock of the type employing a tapered rotatable plug, the cock being constructed in accordance with one embodiment of the invention.

Fig. 2 represents a section through the 60 casing for a cock, the casing in this instance having its working face provided with a lubricant, and

Figs. 3 and 4 are detail views of plugs for cocks of the type shown in Figs. 1 and 65 2, the plugs in Figs. 3 and 4 being shown provided with lubricant.

Similar parts are designated by the same reference characters in the several views.

The present invention is applicable generally to cocks or valves of the type employing a casing and a rotatable plug, it being especially applicable to cocks of this type wherein the plug is tapered, the plugs of the latter type having a pronounced tendency to stick in their casings, owing to their taper form. The invention has particular advantages as applied to cocks or valves employed in gas fixtures or connections, as the gas has a tendency to keep the working 80 faces of the valve or cock dry, and these faces when in such condition are particularly liable to stick and thus render difficult rotation of the plug. The lubricant, according to the present invention, may be applied in different ways, either to the working face of the plug, the working face of the casing, or, if desired, to the working faces both of the plug and the casing. Certain embodiments of the invention are 85 shown in the accompanying drawing and will be hereinafter described in detail, but it is to be understood that the invention is not restricted to these embodiments of the invention, other or equivalent constructions 90 being contemplated and these will be included within the scope of the claims.

In the present instance, 1 designates the casing of a cock or valve having connections 2 and 3 for the pipes which convey the gas 100 or fluid to and from the cock. The casing has a valve seat 4 which, as shown, is con-

2

cal. The plug 5 is adapted to rotatably fit in the casing, it having a conical form corresponding to and fitting the conical seat 4 in the casing. The plug may have an angular portion 6 or a handle or any other equivalent means for rotating it and it may have any suitable means to retain it in proper fitting relation with the casing, the smaller end of the plug in the present instance being provided for this purpose with a threaded portion 7 to receive a nut 8, and this nut may bear on a washer 9 which surrounds the lower end of the plug and bears on the adjacent portion of the casing. As usual with cocks or valves of this type, tightening of the nut 8 draws the conical or tapered plug into close fitting relation with the conical seat in the casing, and such close fitting relation between the plug and casing is maintained by the nut. As usual in cocks or valves of this type, the plug has a diametrical or other port 10 therein which establishes or interrupts communication between the inlet and outlet of the cock, according to the position of rotation of the plug in the casing.

The means provided in the construction shown in Fig. 1 for maintaining efficient lubrication of the working faces of the plug and casing consists of a helical groove 11 which has a pitch toward one end of the plug and a helical groove 12 which has a pitch in a reverse direction or toward the opposite end of the plug, in consequence of which the grooves intersect at intervals along the length of the plug. A lubricant 13 which is in solid form fills these grooves to a depth that will bring the lubricant flush with the working face of the plug, the lubricant thus forming in effect a part or a continuation of the working face of the plug. The grooves and the lubricant preferably extend throughout the area of the working face of the plug which comes in contact with the casing, and the grooves and the lubricant preferably extend continuously in a direction circumferentially of the plug, except at the points where the port 10 in the plug meets the circumference of the plug, at which points it is preferable to interrupt the grooves and also the lubricant to provide uninterrupted or continuous metal margins 14 and 15 which surround the ends of the port 10. The advantage of this construction is that proper gas-tight fits of those portions of the plug surrounding the ends of the port 10 will be maintained with the working face of the casing without depending upon the lubricant to maintain such fit. The lubricant employed is of a solid form and of a character capable of maintaining such form and efficient lubricating properties, irrespective of the age of the lubricant or temperature conditions. Graphite in dense form is pref-

erably used, the graphite being compressed 65 under heavy pressure into the grooves.

In the embodiment of the invention shown in Fig. 2, the casing has its working face 4 formed with a helical or spiral groove 16, and a lubricant 17 in solid form, such as 70 graphite, fills the groove to a depth where the lubricant will be flush with and thus form a part or a continuation of the working face of the casing. In this instance, the groove and the lubricant are preferably interrupted at points adjacent to the ports 18 and 19 in the casing, thus leaving continuous or uninterrupted metal margins 20 and 21 surrounding the ports 18 and 19 to prevent leakage of fluid or gas without depending on 80 the lubricant to maintain such joints. The plug to be used in cases such, for example, as that shown in Fig. 2, where the working face of the casing is provided with the lubricant, may be either plain or it may have a lubricant 85 contained in pockets formed in its working face.

Figs. 3 and 4 show examples of plugs adapted to be used either with a casing the working face of which is plain or unlubricated as, for example, shown in Fig. 1, or in cases where the working face of the casing is lubricated, as shown, for example, in Fig. 2. In Fig. 3, the working face of the plug is formed with a helical groove 22, and the lubricant in solid form such, for example, as graphite, fills this groove to a depth where the lubricant will be flush with the working face of the plug and hence will form a part or a continuation of this working face. The 95 groove and the lubricant in this instance are shown as interrupted adjacent to the margins of the plug where the ends of the port 10 therein meet the circumference of the plug, thereby providing continuous or uninterrupted metal margins 24 and 25 surrounding the ends of the port 10 to maintain the necessary gas-tight fit with the casing without depending on the lubricant for this fit. In the construction shown in Fig. 4, the 100 working face of the plug is formed with a suitable number of grooves 26 which are spaced circumferentially of the working face of the plug, and each groove has a helical pitch whereby the groove extends part way. 105 around the plug. Smaller pockets 27 are formed at intervals in the spaces between the grooves 26 in the working face of the plug. Bodies of lubricant 28 and 29 (the lubricant being in solid form) fill the 110 grooves 26 and the pockets 27 respectively to a depth that will bring the lubricant flush with the working face of the plug, and the lubricant will form a part or a continuation 115 of the working face of the plug. In this embodiment of the invention, the grooves or pockets do not extend around the plug sufficiently to permit any leakage of gas or

fluid past the plug, or in other words, the metal working face of the plug provides substantially continuous or uninterrupted margins which surround the ends of the port 10 5 in the plug.

In any case, the lubricant is of a character which will maintain efficient lubricating properties, irrespective of the temperature conditions or the age of the lubricant, and by 10 providing the working face of the plug or the working face of the casing, or the working faces of both the plug and the casing with lubricant-containing grooves or pockets, efficient distribution of the lubricant relatively to these working faces is provided 15 and maintained.

I claim as my invention:—

1. In a cock comprising a casing and a tapered plug rotatably fitted therein, the 20 casing and plug having contacting working faces, means for lubricating the tapered contacting working faces of such parts embodying bodies of solid lubricant contained in a plurality of helical grooves in one of said 25 working faces.

2. Means for preventing seizing of the working faces of a cock having a casing and a tapered plug rotatable therein, the casing and plug having contacting fluid-tight 30 working faces, said means comprising a lubricant in solid form set into and retained in one of said tapered working faces in parallel helical grooves.

3. Lubricating means for the working 35 faces of cocks of the type employing a casing and a plug rotatable therein, the casing and plug having contacting fluid-tight working faces, such means comprising bodies of solid

graphite filling parallel helical grooves in one of said working faces, the graphite being flush with and constituting a continuation of the working face containing it. 40

4. The combination with a cock comprising a casing having a tapered ported seat formed directly therein, and a tapered ported plug rotatably fitting said tapered seat, said seat and plug having contacting working faces, of means for lubricating and preventing seizing of such contacting working faces of the plug and casing embodying 45 a lubricant in solid form contained in and retained by helical pockets formed in one of said faces, the lubricant filling the pockets to a depth flush with the working face containing it, and the lubricant containing 50 pockets being interrupted adjacent to the ports of the respective working face. 55

5. Lubricating means for the working faces of cocks embodying a ported casing and a ported plug rotatable therein, the casing and plug having contacting working faces, such means comprising a lubricant in solid form contained in helical grooves formed in one of said working faces to a depth flush with such working face, the lubricant-containing grooves being interrupted to provide a continuous margin in 60 said face around the respective port. 65

In testimony whereof I have hereunto set my hand in presence of two subscribing witnesses. 70
